US0D1072447S

(12) **United States Design Patent** (10) **Patent No.:** **US D1,072,447 S**
(45) **Date of Patent:** **** Apr. 29, 2025**

(54) **INSOLE**

(71) Applicant: **Changhua Zhao**, Zhuji (CN)

(72) Inventor: **Changhua Zhao**, Zhuji (CN)

(**) Term: **15 Years**

(21) Appl. No.: **29/955,173**

(22) Filed: **Jul. 31, 2024**

(51) LOC (15) Cl. **02-04**

(52) U.S. Cl.

USPC **D2/961**

(57) **CLAIM**

The ornamental design for an insole, as shown and described.

DESCRIPTION

FIG. 1 is a front perspective view of an insole, showing my new design;

FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom view thereof;

FIG. 8 is an enlarged portion view labeled, “8,” in FIG. 1; and,

FIG. 9 is an enlarged portion view labeled, “9,” in FIG. 1. The even dashed broken lines in the drawings illustrate the portions of the insoles, which form no part of the claimed design.

The dash-dot-dash broken lines encircling the enlarged views are for annotative purposes only and form no part of the claim thereof.

1 Claim, 9 Drawing Sheets
